BAG FILLING SPOUT

Arno Andreas, Munster, Germany

Application October 22, 1931, Serial No. 570,331
In Germany December 8, 1930

7 Claims. (Cl. 226—48)

This invention relates to spouts or nozzles for package filling machines, and more particularly to improvements in spouts for filling valve bags with pulverulent materials, such as cement, and for permitting air in the bags to escape therefrom. A nozzle of this type is shown in my co-pending application, Serial No. 508,450, filed January 13, 1931, and the features disclosed in the present application are illustrated in connection with such a nozzle, with which they are combined to especial advantage, though it will be understood that, for the most part, they are susceptible of embodiment in other styles of nozzles.

As is well known, the practice is to use a nozzle the upper wall of which extends out beyond the lower wall, with its outer end preferably turned downwardly. In placing valve bags on such a nozzle or spout so that they depend therefrom, with the flaps in the bags for closing the valve openings lying along the lower side of the spout, the result has been, especially with bags of soft material, that the flap or adjacent portion of the bag has frequently become stuck on the spout, sometimes ripping the bag and, more often, at least irritating the operator and causing delay. One of the objects of the invention hence resides in the provision of improvements in spouts which are simple and inexpensive to make and which avoid these disadvantages.

Another object of the invention is to increase the efficiency of the means for propelling the material through the spout, by a novel construction of the spout and adjacent outlet opening in said means.

A further object is the provision of simple and effective means for carrying away the dust which is bound to escape with the air from the bags when they are being filled with materials such as cement.

Still another object of the invention has to do with a simple and improved spout construction for cooperation with means for clamping the bag on the spout.

Other objects and advantages of the invention will be apparent from the following detailed description of a preferred embodiment, reference being had to the accompanying drawings, where-in Fig. 1 is a side elevation, partly in section, of one form of my improved construction. Fig. 2 is a front elevation of the construction shown in Fig. 1. Fig. 3 is a section, on the line 3—3 of Fig. 1, partly broken away, through a filling nozzle on spout, with the bag thereon, looking toward

the outlet end of the nozzle. Fig. 4 is a view similar to Fig. 3, except that it shows a modified type of bag, and clamp therefor. Figs. 5 and 6 are details of the construction shown in Figs. 1 and 2, and Figs. 7 and 8 are details of a modified 5 spout.

There is shown at 1 a propeller or turbine housing for the propeller 2 on shaft 3. A propeller blade is indicated at 4, and the outlet opening in the propeller housing at 5. Secured to the housing 1 by bolts 6 is an arm 7 for carrying shaft 9. Journalled on shaft 9 is a sleeve 10 to which is secured arm 11 having a handle portion 12. Also secured to the sleeve 10 is a depending arm 13 provided near its lower end with a set screw 14 and a lock nut 15. Arm 7 is formed with bifurcated portions 8 between which there is pivoted on shaft 9 a bag clamp, which consists of a member 16 having an extension 17 against which a bag gripping element 18 is secured by 20 bracket 19 and screws 20. Element 18 is composed of resilient material such as rubber. Element 18 is so arranged with respect to member 16 that its bag engaging surface is parallel to the bag when the center of gravity of member 18 25 and the parts carried therewith, is rearward of the pivot point of the member, so that the bag is gripped over a considerable area while the member 16 is still tending to swing forward. In this way, a superior gripping action is achieved. 30 In Fig. 1, a bag 21 with flap 22 for closing the valve opening is shown retained on the spout 23 in position for filling. This spout is tubular, as shown, and is provided at its inner end with a flange 24 secured to it in any suitable manner. 35 Bolts 25 secure the spout flange to the propeller housing.

When the bag has been filled with the desired quantity of material, the operator pulls down the handle 12 so as to cause the end of the screw 14 40 to abut against member 16 with the result that the bag clamp will be swung backwardly and upwardly to release the bag. Screw 14 is adjusted so that the clamp will be released at the desired 45 point in movement of the handle. The bag having been removed from the machine, the next step is to place an empty bag on the spout. This is done by simply slipping the valve opening in the bag over the spout, whereupon the bag clamp will swing under the influence of its own weight 50 to clamping position and thereby automatically clamp the bag. If desired, at any time, the operator may assist by giving the clamp a slight forward pull. In machines where the propeller is rapidly rotated, whether the feed be periodically 55

cut off at the inlet side or the outlet side of the propeller, it has been found that the pressure of the material which the propeller delivers aids the clamping action by urging the bag slightly 5 outwardly.

In order to provide a single-walled spout which achieves substantially the advantages of the more expensive double-walled spout, heretofore suggested, I have devised a construction which preferably comprises a tube 23 having one or more longitudinally extending ribs 26 at its lower side for forming air passages between the spout and the adjacent portions of the valve bags when on the spout for filling, the ribs having rounded surfaces to prevent cement or the like from sticking to them. The spout has a lower wall 29 which terminates, as is customary, short of the upper wall 30, with respect to the outlet end of the spout, the latter wall terminating in a downwardly extending tip 31. A spout of this character is shown in my application #508,450, referred to above. In order to prevent valve bags from catching on such spouts when the operator hurriedly attempts to put them in place, and at the same time to allow for undiminished flow of material, I have provided a rib 32 which extends from the end of the lower wall upwardly and outwardly to meet the upper wall adjacent its tip, and which may especially advantageously be 25 made as an extension of and integral with rib 26. A plurality of these ribs may be used as shown in Figs. 7 and 8. For securing the bags to the spout during filling operations, by means of a clamp such as has been described, I have found it 30 desirable to form a clamping surface on the spout. This surface is best formed as a flat portion 28 on the top of the spout adjacent its outer end, and has particular advantages with a single-walled, ribbed tube, because of the absence of 35 difficulties inherent in forming a double-walled tube in this way.

As shown in Figs. 2 and 3, the resilient gripping element 18 may be so located on the clamp 16 as to engage the bag substantially in the middle 40 of the flat top portion 28 of the spout. However, where seamed bags having an upper seam projection 33 (such as shown in Fig. 4) are to be employed, a clamp having the gripping element laterally offset may be utilized, said gripping 45 element cooperating with a part of the portion 28 at one side of the center thereof, as illustrated in Fig. 4.

For collecting the dust which inevitably escapes with the air from the bag when powdered or finely divided materials are being filled into bags, I have provided a generally annular housing 33 for surrounding the nozzle at its end adjacent to propeller housing. This annular housing preferably has a larger diameter than the spout so 50 that there is space between the spout and the housing. The inner side of the housing may abut against the spout flange and be secured thereto by any suitable means. The bottom of the housing flares into a tube 34, preferably integral therewith, for carrying the dust to any desired point with or without use of suction. In this construction, the fine dust which passes alongside the rib or ribs 26 is collected in the housing 33 and passes out through tube 34. I have found this construction simple and effective 55 and especially advantageous on account of the ease with which it may be assembled. If it is desired to remove the housing at any time, it can 60 be slipped over the spout. Suitable suction

means and a dust collector (not shown) may be operatively connected with tube 34.

It sometimes happens that when the propeller is rotating in a considerable mass of material, the material tends to clog or choke the opening in the propeller housing which leads into the spout. I have found that this disadvantage is greatly overcome if the size of the opening 5 in the propeller housing is somewhat smaller than the cross-section of the spout, the latter being generally determined by the size of the valve opening in the standard valve bags at present in use. Hence, it is advantageous to construct the housing and adjacent spout in this way, as best illustrated in Fig. 1. 15

It has been found desirable to have the lower wall of the spout longer than the valve flap on the bag, as shown, to avoid an "injector action", or in other words, the tendency of the incoming material to draw in air. At the same time the 20 sidewalls of the spout may be cut back as shown in Figs. 7 and 8 to allow for expansion of the material.

The terms and expressions which I have employed are used as terms of description and not of 25 limitation, and I have no intention, in the use of such terms and expressions, of excluding any equivalents of the features shown and described or portions thereof, but recognize that various modifications are possible within the scope of 30 the invention claimed.

Certain features are shown but not claimed herein because they are claimed in my copending applications.

What I claim is:

1. A spout adapted to enter the opening in a valve bag for filling the bag and including a lower wall terminating short of the upper wall, with respect to the outlet end of the spout, and a rib meeting the outer end of the lower wall 40 and extending to meet the upper wall adjacent its outer end.

2. A spout of the character described adapted to enter the opening in a valve bag and comprising a tube for conveying material having its 45 lower wall terminating short of its upper wall with respect to the outlet end of the spout, and a rib extending generally longitudinally of the spout and including a portion adapted to form air passages between the valve and the tube, 50 and a portion extending from adjacent the outer end of the lower wall to a point adjacent the outer end of the upper wall and being secured to said outer end of the upper wall.

3. A spout of the character described adapted 55 to enter the opening in a valve bag and comprising a tube for conveying material having its lower wall terminating short of its upper wall with respect to the outlet end of the spout, and a rib extending generally longitudinally of the 60 lower wall of the spout and including a portion adapted to form air passages exterior to said rib and between the valve and the tube, and an extension of said rib extending from the outer end of the lower wall to a point adjacent the 65 outer end of the upper wall.

4. In a bag filling machine, a single-walled spout adapted to enter an opening in the bag, a rib formed on the bottom of the spout, a flat portion on the top of the spout, and means to 70 clamp a bag against the flat portion when the bag is on the spout.

5. In a bag filling machine, a spout adapted to enter an opening in the bag, a flat portion formed on the upper wall of the spout and means 75

to clamp a bag against the flat portion when the bag is on the spout.

6. In a bag filling machine, a spout adapted to enter an opening in the bag, a flat portion formed on the upper wall of the spout, and means co-operating with a part of said flat portion at one side of the center thereof for clamping the bag to said spout.

7. In a bag filling machine, a spout adapted to enter an opening in the bag, a flat portion formed on the upper wall of the spout, and means co-operating with the middle of said flat portion for clamping the bag to said spout.

5
